UNITED STATES PATENT OFFICE.

CHARLES B. MORROW, OF CHICAGO, ILLINOIS.

DESIGN FOR A DISPLAY-RING.

SPECIFICATION forming part of Design No. 31,156, dated July 4, 1899.

Application filed February 10, 1899. Serial No. 705,216. Term of patent 3½ years.

To all whom it may concern:

Be it known that I, CHARLES B. MORROW, a citizen of the United States, residing at Chicago, in the county of Cook and State of Illinois, have invented and produced a new and useful Design for Display-Rings for Fabrics and Like Articles, of which the following is a specification, reference being had to the accompanying drawing.

10 The figure is a perspective view of a display-ring embodying my design.

The leading feature of this design consists of a circular band ring A, provided on its outside with spring-clips B, which are attached

near its upper edge. These spring-clips are 15 made in the form of loops and depend from their upper ends alongside of the ring A. The spider-arms C C extend radially inward and upward from the interior of the ring A and are wound so as to form a loop D at their 20 meeting point.

What I claim as my invention is—

The design for a display-ring as described and shown.

CHARLES B. MORROW.
